[57] ABSTRACT

A contact spring index system for timepieces comprises a simplified indexing arrangement wherein an oscillating balance wheel activates a contact spring to directly drive the seconds wheel of the timepiece. More specifically, the drive means for the timepiece oscillates the balance wheel at a predetermined frequency while a contact pin mounted on the balance wheel periodically displaces a cantilevered contact spring. The displaced contact spring engages and drives a ratchet wheel in a predetermined manner. The ratchet wheel is mounted on a shaft which includes a worm gear portion in direct engagement with the seconds wheel of the timepiece. Thus, the balance wheel motion is directly transmitted by the contact spring to the timing wheels of the timepiece.

CONTACT SPRING INDEX SYSTEM FOR TIMEPIECES

BACKGROUND OF THE INVENTION

The present invention relates to timepieces and particularly to an improved indexing system for electric timepieces.

The prior art includes various indexing systems for use in watches. Typical arrangements are disclosed in Stephenson U.S. Pat. No. 40,508 which issued Nov. 3, 1863 and Wensch U.S. Pat. No. 247,721 which issued Sept. 27, 1881 wherein displacement of a spring or lever by a balance wheel is utilized to drive an escapement mechanism.

German OLS 1,673,770 dated Apr. 25, 1967 in the name of Manfred Grozinger discloses an indexing apparatus wherein a tooth member affixed to one end of the watch stem forces a contact spring into engagement with an index wheel for driving purposes. Further exemplary of the art is U.S. Pat. No. 1,772,556 to A. F. Poole which issued Aug. 12, 1930 disclosing the use of a pawl and worm gear in an indexing device. Also of interest are U.S. Pat. No. 2,976,673 to Petters et al which issued Mar. 28, 1961, U.S. Pat. No. 3,153,896 to Smulski which issued Oct. 27, 1964 and U.S. Pat. No. 3,184,910 to Laviolette which issued May 25, 1965. These patents disclose various limited features in the indexing art and have been cited herein as of general interest. The prior art mentioned above is not intended to be an all inclusive listing of pertinent prior art patents but merely is intended to state the more pertinent prior art which has come to applicant's attention.

The present invention comprises an extremely simple and advantageous indexing mechanism which differs considerably from the prior art discussed above. In this invention, the seconds wheel is in direct engagement with the worm gear portion of the ratchet shaft utilizing relatively few and inexpensive parts to provide an extremely accurate timepiece design.

SUMMARY OF THE INVENTION

The present invention pertains to a contact spring index system for timepieces wherein a contact pin on an oscillator balance wheel activates a cantilevered contact spring to directly drive an indexing arrangement. In the preferred embodiment, an electric motor for the timepiece drives the balance wheel at a predetermined frequency. A contact pin which projects outwardly from the balance wheel displaces the free end of the contact spring preferably with a slight lifting motion. The displaced contact spring indexes a ratchet wheel shaft which drives the seconds wheel of the timepiece via a worm gear portion on said shaft. The axis of the ratchet wheel may be off-centered with respect to the balance wheel staff to impart added lift to the contact spring and thereby improve the functioning of the ratchet wheel.

Accordingly, an object of this invention is to provide a new and improved indexing system for timepieces.

Another object of this invention is to provide a new and improved contact spring means for directly driving an indexing arrangement.

A more specific object of this invention is to provide a new and improved indexing means for an electric timepiece wherein a contact spring is activated by an oscillating balance wheel to directly drive a ratchet wheel coupled to the seconds wheel of the timepiece.

BRIEF DESCRIPTION OF THE DRAWINGS

Other objects and advantages of this invention may be seen from the following description when viewed in conjunction with the accompanying drawings wherein:

FIG. 1 is a simplified perspective view of the indexing system comprising the present invention with conventional portions of the timepiece omitted.

FIG. 2 is a partial top view of the indexing system of FIG. 1 illustrating the relationship of the contact pin and contact spring in effecting movement of the ratchet wheel.

FIG. 3a-3d illustrate sequentially and in a simplified manner the driving of the ratchet wheel by the contact spring.

FIG. 4a and 4b illustrate the functioning of the ratchet wheel and contact pin in somewhat greater detail; and

FIG. 5 illustrates the improved functioning of the system due to an offcentered index wheel.

DETAILED DESCRIPTION OF THE INVENTION

Referring now to the drawings, the invention comprises an indexing system 10 for timepieces of the electric or electronic type. Since the invention is suitable for use with numerous timepiece designs and the details of such timepieces are conventional and well-known, only the specific elements of the invention are shown in the drawings. For example, the balance wheel 11 is mounted to staff 12 and includes a coil 13 mounted thereto. The balance wheel 11 is oscillated back and forth about the staff axis by a drive means or circuit (not shown) which interacts with the coil 13. The details of such drive means being within the skill of the art are omitted from the representation of FIG. 1.

The balance wheel 11 includes a mounting or contact 14 having a contact pin 16 projecting downwardly therefrom. The pin 16 may be mounted for rotation or fixedly mounted so that it remains in place as it engages the free end 17 of the contact spring 18. The other end 19 of the contact spring 18 is fixedly mounted in an insulated contact block 21 so that the spring is cantilevered outwardly therefrom. The free end 17 of the spring 18 is displaced by the contact pin 16 as the balance wheel oscillates back and forth in the manner shown in FIG. 4a.

A ratchet wheel 22 is mounted on the end of a shaft 23 which is positioned substantially parallel to the contact spring 18. The shaft 23 also includes an intermediate worm gear portion 24 which engages the seconds wheel 25 of the timepiece. The seconds wheel 25 is, of course, coupled to the minutes wheel and hour wheel of the timepiece in a convenient manner so that the driving movement of the balance wheel 11 is transmitted to the watch indicating means (not shown) via the disclosed indexing arrangement.

In operation the contact pin 16 on the oscillatory balance wheel 11 engages the end 17 of the contact spring 18 as shown in FIG. 3a. As the balance wheel 13 oscillates in the direction of the arrow in FIG. 3b, the ratchet wheel is indexed thereby. FIG. 3c shows the end 17 of the contact spring 18 at rest while FIG. 3d shows the return movement of the spring as the balance wheel 13 is oscillated in the opposite direction.

As shown in greater detail in FIG. 4a and 4b, the balance staff axis 26 and the axis 28 of the ratchet wheel 22 are in substantially the same plane. The contact

spring 18 is shown in solid lines in a rest position and in dashed lines in its forward and rear positions. It is noted that the ratchet wheel 22 is driven in only one direction as the spring engages tooth 27 under urging of the pin 16.

FIG. 5 shows the advantage of off-centering or offsetting the axis 28 of the ratchet wheel 22 with respect to the balance staff 12 in another preferred embodiment. The off-centering has the effect of creating an improved tooth/spring working condition by reducing the lifting of the contact spring 18 by the distance 31 during the reverse movement of the balance wheel 11 and as the spring end 17 clears the tooth 33. The distance 35 represents the lift up distance of the spring end 17 during the reverse movement of the balance wheel 11. After the return movement, the spring 18 moves the wheel 22 in the indicated direction as the balance wheel 11 moves forward. Thus the wheel 22 is driven in a single direction.

As the ratchet wheel 22 is indexed by the contact spring 18, the intermediate worm gear portion 24 on the ratchet shaft drives the meshing seconds wheel 25 of the timepiece. The seconds wheel 25 is coupled to the other timing wheels in a conventional arrangement so that the indicating means are driven thereby. The indexing means 10 of the present invention thus permits a simple and inexpensive direct drive from the balance wheel 11 which is suitable for use in highly accurate timepieces of the quartz crystal type.

While the invention has been explained by a detailed description of certain specific embodiments, it is understood that various modifications and substitutions can be made in any of them within the scope of the appended claims which are intended also to include equivalents of such embodiments.

What is claimed is:

1. An indexing system for timepieces having a drive means coupled to said system comprising:
an oscillatory member driven by said drive means and having contact means mounted thereon,
a contact spring fixedly mounted at one end and having the other free end periodically engaged by the contact means during the movement of the oscillatory member,
a shaft rotatably mounted within the timepiece and adjacent the contact spring, said shaft having a

worm gear portion and a ratchet wheel mounted to be engaged and driven by the contact spring, and timing means engaging the worm gear portion of the shaft to be indexed thereby when the contact spring drives the ratchet wheel under urging of the contact means on the oscillatory member.

2. An indexing system for timepieces having a drive means coupled to said system in accordance with claim 1 wherein:

the oscillatory member comprises a balance wheel and the contact means comprises a pin extending outwardly from the balance wheel.

3. An indexing system for timepieces having a drive means coupled to said system in accordance with claim 1 wherein:

the contact spring is an elongated flexible member extending substantially parallel to the shaft.

4. An indexing system for timepieces having a drive means coupled to said system in accordance with claim 1 wherein:

the timing means comprises a seconds wheel meshing with the worm gear portion of the shaft and being driven thereby, minutes and hours means being coupled to said seconds wheel, and indicating means driven by the respective seconds wheel and minutes and hours means.

5. An indexing system for timepieces having a drive means coupled to said system in accordance with claim 1 wherein:

the axis of the ratchet wheel is off centered with respect to the axis of the balance shaft to impart increased lift to the contact spring so that it readily clears the ratchet wheel during its movement in a reverse direction.

6. An indexing system for timepieces having a drive means coupled to said system in accordance with claim 1 wherein:

the contact pin is fixedly mounted adjacent the balance wheel and is driven thereby.

7. An indexing system for timepieces having a drive means coupled to said system in accordance with claim 1 wherein:

the ratchet wheel includes a plurality of teeth which are designed so that the teeth are engaged by the contact spring to be driven in one direction.
